UNITED STATES PATENT OFFICE.

FRANS AUG. FRANZÉN, OF LUND, SWEDEN.

ROLLER-GEARING.

1,282,563.

Specification of Letters Patent. Patented Oct. 22, 1918.

Application filed May 21, 1918. Serial No. 235,871.

To all whom it may concern:

Be it known that I, FRANS AUGUST FRANZÉN, a citizen of Sweden, and resident of Lund, Sweden, have invented new and useful Improvements in Roller-Gearings, of which the following is a specification.

My invention relates to a noiseless running gearing based upon the theory of the straight epicycloidal motion. The gearing 10 consists of two wheels engaged in each other and one of them being provided with rolls running in slots diametrically arranged in the other wheel. The relation between the sizes of the pitch-circles of the wheels is 1:2, 15 and thus the relation between the numbers of revolution of the shafts will be 1:2, though the ratio of gearing may be altered by using two or more roller gearings of the same kind.

20 The characteristic feature of the invention is that the wheel provided with rolls consists of two plates between which the pins carrying the rolls are mounted and that the slots in one of the wheels are arranged radially through a flat plate or disk extending from the circumference of the wheel, said flange being in the same plane as the rolls. By this arrangement a regular and noiseless running is obtained and the durability of 25 the apparatus is increased. The invention 30 comprises also certain details the construction and object of which are hereinafter set forth and claimed.

Referring to the drawings,—Figure 1 35 shows a longitudinal section of the apparatus; Fig. 2 is an end view of the same. Fig. 3 is a longitudinal section of a modified form of the invention, and Fig. 4 is an end view of the same; Fig. 5 is a detail view of 40 the latter, and Figs. 6, 7 and 8 show the same in modified forms.

According to Figs. 1 and 2 the apparatus 45 consists of a casing 1 in two parts that may be separated from each other and in which the two shafts 2 and 3 are journaled. If the ratio of gearing is fixed to 1:2 the shaft 2 is supposed to be the driving shaft with the higher number of revolutions and the shaft 3 the driven one with the lower number 50 of revolutions. The driven shaft 3 is provided with a cup shaped wheel 4 carrying an annular plate or flange 5 extending from its circumference toward the shaft and provided with slots 6 cut right through the same and open toward the shaft. The num-

ber of slots is eight in the form shown. On the driving shaft 2 two plates 7 and 8 are fastened said plates carrying journals 9 for cylindrical rolls 10 the latter having a diameter a trifle smaller than the width of the 60 slots 6. The plates 7 and 8 are kept together at the center of the shaft 2 that is here reduced to a pin of so small a diameter that the plate 5 can rotate freely without the parts thereof between the slots 6 striking 65 against said pin. Thus the plates 7 and 8 which form a wheel carrying the rolls 10 are placed one on each side of the flange 5, and the rolls 10 are placed in the same plane as said flange.

As the number of the slots 6 is eight four rolls 10 must be provided for and said rolls will always travel in a straight line relatively to the plate 5 coinciding with the diameter of the plate. Of course, the pitch 75 may be varied in such a way that a greater or smaller number of rolls and slots are used, but the number of rolls must always be half of the number of slots.

On account of the rolls 10 traveling diametrically in relation to the plate 5 no shocks arise in the direction of rotation and thus the apparatus runs noiselessly. The rolls being slightly smaller than the slots only touch one of the sides of the slots and 80 roll over the same without touching the opposite side. The casing 1 is completely closed and filled with oil that is caught by the plate 5 in such a way that the apparatus is lubricated automatically. In order to 90 further reduce the friction ball bearings may be provided for the journals 9 instead of the rolls, the outer rings of said ball bearings serving as rolls. The journals 9 as well as the rolls 10 and the plate 5 consist of hard 95 steel and the other parts may be made of a softer and cheaper metal, for instance of cast iron.

In order to obtain a theoretically true running by means of a gearing of the kind referred to it is necessary that one of the shafts does not vibrate in relation to the other one as might be the case especially when the apparatus is to be used for transmitting of larger amounts of power and at 100 greater velocities, as the shaft carrying the rolls is journaled only at one side of the working surface of the rolls. Moreover the rolls are rotated in one direction at their entrance into the slots and in the opposite 105 110

direction when they leave the slots. After having left the slots the rolls will continue to rotate in the latter direction on account of their inertia and when they are entering into the slots again they rotate in a direction opposite to the direction required for their rolling into the slot without friction. This circumstance causes a shock that results in the vibration mentioned above. These disadvantages are avoided by the present invention by the shaft carrying the rolls on both sides of the working surfaces of the rolls and by braking the rolls after their leaving the slots and giving them an opposite direction of rotation. In this way all shocks and irregular vibrations are avoided irrespective of the amount of power to be transmitted and of the velocity.

The gearing consists, as shown in Figs. 3 and 2, of two shafts 13 and 14 in a common casing 12, one of said shafts 14 carrying a slotted disk or flange 15 and the other one 13 a number of rolls 18 mounted in two flanges 16 and 17 firmly connected with the shaft 13. As stated above the diameter of the disk is twice as large as a circle drawn through the axis of rotation of the rolls 18 and thus the latter travel in the slots according to the theory of the straight epicycloid in such a way that the ratio of gearing is 1:2.

According to the invention a bearing 23 carries the inner free end 19 of the shaft 13 and said bearing is provided in a bent arm 20. The part of the arm perpendicular to the shaft is placed inside the inner flange 17 of the shaft 13 in the cup shaped flange 21 that is connected with the shaft 14 and carries the slotted disk 15. The part of the arm 20 parallel with the shaft is in a suitable way fastened to the casing 12. This is made possible by means of arranging the plates 16 and 17 eccentrically in relation to the disk 15 in such a way that an interspace is formed between them. In order to support the arm 20 and the bearing 23 a pin 22 may also be provided on the arm in such a way that it has its bearing in a boring in the shaft 14, as shown in the drawing. In this way the shafts may be subject to vibrations and when 50 vibrating at greater velocities they will do it uniformly and together in such a way that the function of the gearing is not disturbed. Of course, a similar effect may be obtained if the shaft 14 is prolonged and the arm 20 is provided with a bearing.

For the purpose of reversing the direction of rotation of the rolls one of the journals on each roll is extended and provided with a brake wheel. In the form shown the journals 24 nearest to the arm 20 are extended and on their outer ends brake wheels 25 are provided, said wheels eventually having profiled surfaces for the purpose of increasing the friction. A fixed curved brake member 26 is fastened to the arm 20 concentric with

the shaft 13 said brake member having the same cross profile as the brake wheels. The brake member has such a length and is arranged in such a way that the brake wheels strike the same at the same time as the rolls 18 leave the slots in the disk 15, and leave the brake member when they enter into the slots. When the brake member 26 is pressed against the wheels 25 the rolls will get stopped in their rotation as they leave the slots in the disk 15 and then their direction of rotation will be reversed in such a way that it coincides with the direction of rotation of the rolls after their entrance in the slots. In this way all shocks at the entrance of the rolls in the slots are avoided and the vibrations are also done away with. The brake member 26 may of course be placed on the outer side of the flanges 16, 17 with the same result and it may be fastened to the casing or to some other part connected with the same, when the opposite journals of the rolls are provided with brake wheels in the manner described. Braking devices may also be provided on both of the said places.

In order to obtain the necessary friction either the brake member 26 itself may consist of elastic material, such as leather, caoutchouc or the like or it may be rigid but elastically fastened to the arm 20 or the casing 15.

According to Figs. 3 and 4 the brake member consists of two rigid segments together forming a semicircle. Said segments are hinged on pins 27 and acted upon from below by a plate spring 28. In this form the shaft 13 must be driving and in this case the velocity of rotation is to be reduced wherefore the brake member is placed between the shaft and the brake wheels. When, however, the shaft 14 is driving and the velocity is to be increased the brake member is placed outside the brake wheels of the rolls, as otherwise the direction of rotation of the rolls would not be reversed in the right way. Of course, the points of view mentioned above in connection with the inner brake member and relating to the pressure and the elasticity, etc., are also applicable in this case. When the brake member is arranged externally the brake wheels may be left out and the rolls themselves used as such, if the brake member is placed opposite the same.

Such a brake arrangement acting upon the rolls 18 or brake wheels 25 is shown in Fig. 6. Here the brake member also consists of a rigid arm 29 pivoted on a pin 30 and acted upon by a spring 31. In order to prevent the brake arrangement from being a hindrance to the rotation of the slotted disk it must be shorter than in the case first described and in order to bring about that at least one of the rolls always may rest against the brake member in such a way that unnecessary and disturbing movements of the lat-

ter may be prevented, the brake member in this case is made in one piece and not in two segments.

The same result can, of course, also be obtained by an integral brake member at inner braking. Such a brake member is shown in Figs. 7 and 8. The brake member here consists of one single piece and is acted upon by spiral springs 33 placed on pins or abutments 34 connected with the brake member, said pins being guided in holes in the arm 20.

Having thus described the invention, I claim:—

1. Roller gearing comprising a casing and a shaft carrying a wheel consisting of two plates between which a number of rolls is mounted, and another shaft carrying a cup shaped wheel provided with a disk extending from the circumference of said wheel toward the shaft and having a number of radial slots open toward the center of the shaft, said rolls engaging in the slots and by rotation of the shafts moving according to the theory of the straight epicycloid.
2. Roller gearing comprising a casing and a shaft carrying a wheel consisting of two plates between which a number of rolls is mounted, and another shaft carrying a cup shaped wheel provided with a radially slotted disk extending from the circumference of said disk toward the shaft, an arm fastened to the casing and extending between the circumference of the plates carrying the rolls and the edge of the slotted disk, and a

bearing on said arm, the shaft carrying the rolls extending through the plates and supported in the bearing.

3. Roller gearing comprising a casing and a shaft carrying a wheel consisting of two plates between which a number of rolls is mounted, and another shaft carrying a cup shaped wheel provided with a radially slotted disk extending from the circumference of said disk toward an arm fastened to the casing and a bearing on said arm, said bearing being located in the hollow end of the shaft carrying the slotted disk, and supporting the shaft carrying the rolls.

4. Roller gearing comprising a casing and a shaft carrying a wheel consisting of two plates between which a number of rolls is mounted, and another shaft carrying a cup shaped wheel provided with a radially slotted disk extending from the circumference of said wheel toward the shaft, an arm fastened to the casing, a bearing on the arm to support the shaft carrying the rolls, and an elastic curved brake member arranged in the casing at such a distance from the shaft carrying the rolls that said rolls strike said brake member when they leave the slots.

In testimony whereof, I have signed my name to this specification in the presence of two subscribing witnesses.

FRANS AUG. FRANZÉN.
